STEPLADDER

Clarence F. Jones, Denver, Colo.

Application April 15, 1946, Serial No. 662,115

1 Claim. (Cl. 228—17)

1

This invention relates to improvements in stepladders and has reference more particularly to a small sized stepladder for use in kitchens and homes.

It is a matter of common knowledge that housewives are required to use a stepladder or a chair in many instances in order to reach the topmost shelves of a kitchen cabinet or in cleaning windows, adjusting curtains and the like.

It is well known that many kinds of stepladders and combination chairs and stepladders have been invented for a similar purpose.

This invention relates in particular to a stepladder which is preferably made from some light metal such as some of the lighter aluminum alloys that have great strength and low specific weight.

Another object is to produce a stepladder that can be attached to the inner surface of the ordinary kitchen sink door in such a way that when the door is closed the stepladder will be hidden away in the space underneath the sink and which, when it is to be used, can be unfolded while still attached to the door.

A still further object of the invention is to produce a stepladder that, in addition to being so constructed that it can be attached to the kitchen sink door both while folded and not in use, and also when unfolded. It can also be removed from the door and used in any place where it is needed.

Having thus briefly described the invention, the same will now be described in detail and for this purpose reference will be had to the accompanying drawing in which the invention has been illustrated in its preferred form, and in which:

Figure 1 is a front view of a kitchen sink showing also a portion of a kitchen cabinet and showing one of the doors in open position;

Figure 2 is a side elevation looking in the direction of arrow 2, Figure 1, and shows the latter in open or operative position;

Figure 3 is a side elevation of the ladder showing the same to a larger scale than that shown in Figures 1 and 2 and shows the parts opened in position for use and showing by dotted lines how the supporting shelf can be held by means of one of the movable parts of the stepladder;

Figure 4 is a side elevation with parts broken away, showing the ladder folded against the door to which it is attached;

Figure 5 is a broken view showing the keyhole slot connected between the stepladder and the door;

Figure 6 is a section taken on line 6—6, Figure 3; and

2

Figure 7 is a fragmentary rear elevation looking in the direction of arrows 7—7, Figure 3.

In the drawing numeral 10 designates an ordinary kitchen sink which is built into a cabinet 5 of ordinary construction and reference numerals 11 designate two doors that are provided for temporarily closing the space underneath the sink. Reference numeral 12 designates the mixing faucet and reference numerals 13 designate the doors of the kitchen cabinet, such as are usually provided above or adjacent to kitchen sinks.

Attached to the inner surface of one of the doors 11 is a stepladder that has been designated 15 in its entirety by reference numeral 14. This ladder is constructed along lines quite common and comprises two side members, each formed from two spaced metal bars 15 between which are positioned steps 16 which are also of metal and are 20 preferably spotwelded to the inner surfaces of the side bars 15.

In the drawing the sides 15 have been shown as flat, but it is the intention to longitudinally corrugate or flute these members to give them 25 additional strength. Since corrugated metal for this purpose is old and well known, it has not been illustrated in detail. Two brace members 17 are pivoted to the parts 15 at point 18 and have been shown as provided with a transverse bar 19 that 30 connects the two braces in the manner shown in Figure 7. It is also contemplated to employ diagonal braces such as are usually employed in connection with stepladders constructed in a similar manner. The diagonal braces have not 35 been shown as they are common and would merely complicate the drawing.

It will be seen that brace members 17 are positioned on the outside of the ladder proper and that, due to the position of the bar 19, they may 40 be folded into a position in which they are superposed on the corresponding ladder support 15, as shown in Figure 4. Sash cord or other flexible members 20 are connected with the inner surfaces of the rear members 15 and to the bar 19 45 in the manner indicated in the drawing. Any other suitable tension members may be employed, such as the usual folding links quite common in connection with stepladders. The stepladder so far described differs very little from the ordinary ladder, except in regard to the material from 50 which it is made.

My improvement consists in providing a shelf or table 21 which is provided at its sides with 55 downwardly extending flanges 22 making the cross section channel shaped. This table is piv-

oted at 18. Another channel shaped member whose side flanges have been designated by reference number 23, is positioned between the sides 22 of table 21 and pivotally connected thereto at 25. The lower ends of the flanges 23 are provided with notches 26 that are adapted to receive the upper edge of cross bar 19, when this member is moved inwardly to the dotted line position shown in Figure 3. The stepladder when detached from the door with the last named channel member in the dotted line position can be used any place around the house. Table 21 serves to support a pan containing cleaning fluid or water or any tools or implements that are to be used.

Normally, the channel pivoted at 25 is attached to the inner surface of door 11 by means of headed bolts 27 that pass through keyhole slots 28 in the manner shown in Figure 5. The parts are so proportioned that when the stepladder is collapsed by moving the table 21 clockwise from the position shown in Figure 3 to the position shown in Figure 4, the upper end thereof will not extend above the top of the door to which it is attached and at the same time the attachment is effected at such a place that when the stepladder is unfolded as shown in Figure 2, the ladder proper, as well as brace members 17 will rest on the floor.

The upper shelves in the kitchen cabinets are usually so high that the housewife must stand on a chair or on a stepladder and they are also usually positioned directly over or to one side of the sink and therefore in order to reach these shelves, the housewife may merely unfold the ladder, as shown in Figure 2, without removing it from the door. If, for any reason the ladder is to be used in any other place, it may be detached and used separately as indicated in Figure 3.

It is to be understood that any usual form of metal construction either longitudinally fluted or with reenforced edges, can be used and applicant does not intend to limit himself to the specific transverse cross section of the material employed by him except insofar as members 21 and 23 are

concerned which are preferably channel-shaped to give rigidity and strength without unduly increasing the weight.

Having described the invention what is claimed as new is:

A stepladder of the type adapted to be secured to a kitchen cabinet door, or the like, comprising: a ladder portion having spaced sides, each side comprising two spaced bars secured together at each step and adjacent their tops and two spaced braces secured by pivot pins to the sides, a table having a flat top and flanges extending along the entire length of the side edges of the top, the pivot extending through said flanges near corresponding ends thereof, whereby the top may be tilted from a substantially horizontal position to a vertical folded position, a cross bar extending between said braces intermediate their ends, a plate pivotally connected to said flanges adjacent their opposite ends, said plate having notch means adapted to engage said cross bar, and cooperative securing means disposed between the side edges of said plate adapted to secure it against the side of the cabinet door, the construction and arrangement being such that when the stepladder is folded the table portion thereof and said plate may be juxtaposed to the door and the entire ladder supported by the door for swinging movement carrying the ladder therewith, and when the ladder is unfolded, the table may be in a horizontal position with the ladder resting on a floor adjacent the door.
